UNITED STATES PATENT OFFICE.

FRANK B. McNINCH, OF PHILADELPHIA, PENNSYLVANIA.

SUCTION AIR-CHAMBER.

986,736.

Specification of Letters Patent. Patented Mar. 14, 1911.

Application filed March 18, 1910. Serial No. 549,661.

To all whom it may concern:

Be it known that I, FRANK B. McNINCH, a citizen of the United States, residing at Philadelphia, in the county of Philadelphia and State of Pennsylvania, have invented a certain new and useful Improvement in Suction Air-Chambers, of which the following is a specification.

My invention relates to a new and useful improvement in suction air chambers, and especially that class of air chambers which are applicable to dental plates or artificial palates, and has for its object to detachably secure the air chamber to the artificial palate, said air chamber having a valve whereby the air remaining in the air chamber after it has been placed in the mouth may be withdrawn, thereby causing an excellent vacuum which draws the plate close to the roof of the mouth.

In accomplishing the above named objects, I construct my device in two parts, the first part being the artificial palate, having a female member vulcanized therein, the second part including a soft rubber air chamber having an outlet, over which is placed a perforated soft rubber diaphragm which acts as a valve for closing the outlet, said air chamber having a male member mounted thereon which snaps into the female member, thereby detachably securing the second part to the first part. A suction air chamber constructed in this manner permits the air which remains in the chamber, after it has been placed in the mouth to be readily withdrawn, so that a vacuum will be obtained, thereby causing the air chamber to collapse and rest against the roof of the mouth, which will draw the artificial palate securely into place, and being detachable, the air chamber may be replaced when worn out.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by letter to the accompanying drawing forming a part of this specification, in which—

Figure 1 is a plan view of my improved suction air chamber. Fig. 2, a section at

the line $x-x$ of Fig. 1. Fig. 3, a longitudinal sectional view of the artificial palate or plate, showing the cap therein. Fig. 4, a plan view of a slightly modified form of my invention in which two valves are employed. Fig. 5, a perspective view of an upper plate showing my invention applied thereto. Fig. 6, a rear view thereof showing the position of the outlet from the valve, and Fig. 7, a perspective view of a lower plate showing my modified form applied thereto.

In carrying out my invention as here embodied, A represents the artificial palate or plate, in which is vulcanized the female member B, having an opening C and provided with an annular groove D which prevents its withdrawal from the plate A and acts as a retainer for the male member, as will be hereinafter described.

E denotes the air chamber of soft rubber which is provided with a flange F entirely around its outer edge, and on this air chamber is mounted the male member G, similar in all details to the member B, with the exception of size, so as to enable the male member to fit within the female member. The air chamber E has a body portion H which entirely fills the cavity in the male member G, and in this body portion is formed an outlet I, from the inner end of which radiate a number of grooves J, said grooves extending to the flange F. Over the male member G is placed a valve or diaphragm K, preferably of soft rubber and is secured in place by cementing its outer edge to the male member, leaving the central portion free to move toward or away from the outer end of the outlet I, and this valve is provided with a perforation L, which is out of alignment with the outlet I so that the valve will close the outlet when a vacuum has been formed in the air chamber.

In practice the male member G will snap into the female member B, the grooves D coinciding in this way holding the air chamber in place under all ordinary conditions.

In placing the artificial palate in the mouth, the air chamber will come in contact with the natural palate, then the suction produced by the tongue and mouth will draw the air from the space between the plate E and the natural palate through the passage way I and the perforation L, forming a vacuum in the air chamber. When the

suction is relieved the valve or diaphragm K will resume its natural position and since the valve is of soft rubber, the tendency will be to enter the outlet I, thus effectually closing said passage way.

In my modified form as shown in Figs. 4 and 7, I have so constructed the device that it can be applied to either the labial or lingual surface of the inferior alveolar ridge. 10 In this modified form of my invention M represents the air chamber of soft rubber, and is formed comparatively long and narrow so that it may be readily applied to either flange of the lower plate. In proximity to both ends is placed a valve, each of which is similar in all details to the one described and shown in Figs. 2 and 3. In the chamber M is formed a groove N which runs the entire length thereof connecting the 15 valves with each other and into this groove run a number of other grooves J' preferably at right angles thereto. This air chamber when in place will have the outlets leading to the side of the plate, as indicated by O, 20 in Fig. 7.

Of course I do not wish to be limited to the exact details of construction here shown, as these may be varied within the limits of the appended claims without departing from 25 the spirit of my invention.

Having thus fully described my invention, what I claim as new and useful, is—

1. In a device of the character described,

a soft rubber air chamber having an outlet leading therefrom, and means for normally closing said outlet. 35

2. In a device of the character described, a soft rubber collapsible air chamber having an outlet and grooves radiating therefrom and provided with an integral flange around 40 its outer edge, and means for normally closing the outlet.

3. In a device of the character described, a rubber air chamber having an outlet, a metallic male member having an annular 45 groove and provided with an opening, and a valve of soft rubber having a perforation mounted upon said male member, the perforation being out of alignment with the outlet. 50

4. In a device of the character described, a collapsible soft rubber air chamber provided with a plurality of outlets and valves for closing said outlets.

5. In combination with an artificial palate 55 having a female member vulcanized therein, of a soft rubber air chamber carrying a valve detachably mounted in said female member.

In testimony whereof, I have hereunto 60 affixed my signature in the presence of two subscribing witnesses.

FRANK B. McNINCH.
